UNITED STATES PATENT OFFICE.

ABRAHAM R. MIRANDA, OF BOSTON, MASSACHUSETTS.

SOAP-HOLDER ATTACHMENT FOR WATER-FAUCETS.

SPECIFICATION forming part of Letters Patent No. 479,330, dated July 19, 1892.

Application filed March 26, 1892. Serial No. 426,578. (No model.)

To all whom it may concern:

Be it known that I, ABRAHAM R. MIRANDA, a citizen of the United States of America, and a resident of the city of Boston, in the county 5 of Suffolk and State of Massachusetts, have invented a certain new and useful Improved Soap-Holder Attachment for Water-Faucets, of which the following is a full, clear, and exact description.

10 This invention consists of a soap-holder attachment for water-faucets, whereby the water from the faucet may, if desired, be discharged with or without being charged with soap, all as hereinafter described, and pointed 15 out in the claim.

In the drawings forming part of this specification, Figure 1 is a plan view of the soap attachment of this invention for a bib cock or faucet. Fig. 2 is a central vertical section, 20 line 2 2, Fig. 1.

25 In the drawings, A represents a bib faucet or cock of any of the usual or other suitable constructions, and preferably such as is used for hot water in the water system of dwelling-houses and other buildings, &c.

30 B is a pipe, which, as particularly shown, is at one end held on and is in continuation of the nozzle A² of the bib, and therefrom passes and opens to the upper portion of a 35 vertical cylindrical vessel C, which has a perforated bottom C² and a hinged top or cap C³ for convenience in opening and closing it.

35 The vessel C is for the soap D, which is to be of any suitable kind, and preferably in comparatively small lumps or pieces, so as the better to be exposed to the water from the bib, and which enters the upper portion of the vessel from the pipe B, and thereby to facilitate and secure the impregnation of the 40 water with the soap, or, in other words, to secure soap suds for discharge at the perforated bottom C² of the vessel to be used as may be desired.

45 The water-pipe connection B of the bib-nozzle A² and the soap-receptacle C has a vertical dip or trap like portion, or, in other words, a descending leg B³ next adjacent to the nozzle and an ascending leg B⁴ next adjacent to the soap-receptacle, both joined at their lower 50 portions or their dip by a more or less horizontal portion B⁵, and all in a manner to re-

duce somewhat the force of the water passing from the bib before it enters the soap-receptacle, and thereby to insure the better charging of the water with soap.

55 E is a discharge-opening located at the horizontal and lowest portion B⁵ of the pipe connection B between the bib-nozzle and the soap-receptacle, and F is a plug or stopper suitable when inserted in said opening E to 60 close said opening and when removed therefrom to open it. This stopper F is attached to one end of a chain G, which at its other end is suitably secured to the soap-receptacle and otherwise, all so that the stopper removed 65 from the opening of the pipe connection is at hand for convenience of being used to close said opening when desired. With the pipe connection of bib-nozzle and soap-receptacle closed at its opening E, the water from the bib 70 then passes into and through the soap in the soap-receptacle and out at its perforated bottom impregnated with soap, or, in other words, as soapsuds. With the stopper F removed from the opening E of the pipe connection of 75 the bib-nozzle and soap-receptacle obviously the water from the bib is discharged before it enters the soap-receptacle, and therefore clear, or, in other words, not impregnated with soap, and the same as if it were directly at 80 and from the faucet.

85 It is plain from the description given of the soap attachment of this invention that either soapsuds or clear water may at pleasure be obtained from it, according as either the one or the other may be wanted, the advantages of all of which when washing dishes and at other times are obvious without particular mention.

90 As particularly shown, the holding of the attachment of this invention on the bib-nozzle is by forcing the open end of the pipe connection over the outside of the nozzle and packing the joint with a piece of rubber tubing H. While this is practical, yet it is not 95 intended to limit this invention as to the attachment described to it, nor to any particular means of holding the attachment either on the bib or otherwise, so that the water passing from the bib shall be run or conducted through the soap-receptacle.

100 Having thus described my invention, what

I claim, and desire to secure by Letters Patent, is—

The combination, with a water-faucet, of a vertical receptacle located at one side of said faucet and at its upper portion adapted to be charged with soap and having a perforated bottom, and a U-pipe in communication at one end with the upper portion of said receptacle and at the other end with said faucet and between the faucet and receptacle and at its

lower portion having a discharge-orifice adapted to be opened and closed, all as described, for the purposes specified.

In testimony whereof I have hereunto set my hand in the presence of two subscribing witnesses.

ABRAHAM R. MIRANDA.
